CAID H. PECK, OF ATHENS, PENNSYLVANIA, ASSIGNOR TO INGERSOLL RAND COMPANY, OF JERSEY CITY, NEW JERSEY, A CORPORATION OF NEW JERSEY.

VALVE FOR PERCUSSIVE TOOLS.

1,089,436.

Specification of Letters Patent. Patented Mar. 10, 1914.

Application filed May 28, 1913. Serial No. 770,296.

To all whom it may concern:

Be it known that I, CAID H. PECK, a citizen of the United States, residing at Athens, in the county of Bradford and State of Pennsylvania, have invented a certain new and useful Improvement in Valves for Percussive Tools, of which the following is a specification.

This invention relates to percussive tools 10 and more particularly to tools of the type used for riveting and the like.

The object of this invention is to produce a tool which will be of high efficiency in operation and, at the same time, consume a 15 comparatively small quantity of the operating fluid.

With this object in view, I have devised a tool a practical embodiment of which is shown in the accompanying drawings in 20 which—

Figure 1 shows a longitudinal section through the tool, Fig. 2 shows a similar section on a larger scale through the valve chest and a portion of the cylinder and Fig. 25 3 shows a transverse section taken on the line III—III of Fig. 2.

The tool is shown as a riveting hammer comprising a cylinder 1 in which reciprocates a piston 2 which strikes on the rivet set 3. To the other end of the cylinder, from the rivet set, is attached the usual handle 4, actuating fluid being admitted therethrough to the inlet passage 5. On the upper side of the tool is a valve chest 6 having a, generally, cylindrical bore into the rear end of which is fitted the rear end 7 of a valve supporting plug 8 the forward part of which is of smaller diameter than the part 7 and projects through the valve chest to the other 35 side thereof. From the forward end of the cylinder a large fluid passage 9 leads to the face of the valve supporting plug 8. A plurality of passages 10 lead through the plug from the passage 9 opening into the 40 valve chest at two points, the exhaust ports 11 and inlet ports 12. The other end 7 of the valve plug is provided with a large inlet chamber 13 which communicates with the inlet passage 5. From the forward end of 45 this inlet chamber, which is of smaller diameter, inlet ports 14, for the rear end of the cylinder, open into the valve chest. Slightly 50 farther forward, the valve plug is increased in diameter forming a flange 15 to the outer periphery of which very small pas-

sages 16 lead from the chamber 13. From the valve chest and so placed as to register with the inlet ports 14, an annular inlet port 17 leads into the cylinder. Farther along the valve chest and farther from the rear end of the cylinder, an annular exhaust port 18 opens into the cylinder, while slightly forward of the annular exhaust port 18 and separated therefrom by a shoulder 19, is an exhaust port 20 opening to the atmosphere through a plurality of passages 21. Sliding in the valve chest on the supporting plug 8, is a valve 22, the forward portion of which controls the exhaust of the tool and the rear portion of which, which is 60 of larger diameter, controls the inlet to the tool. Through the forward part of the valve are ports 23 adapted to connect the exhaust ports 11 and the atmospheric exhaust port 20 when the valve is in its forward position. Just to the rear of these ports is a flange 24 adapted to co-act with the shoulder 19 and close off the port 18 from the port 20 when the valve is in its forward position but which allows the fluid to 65 pass from the port 18 to the port 20 when the valve is in its rearward position, the ports 23 at such a time being out of register with the ports 11. On the inside of the rear portion of the valve is a slight depression 25 which allows communication between the restricted passages 16 and the inlet ports 12 when the valve is in its rearward position. When the valve is in its forward position its rear end uncovers the 70 ports 14 and allows communication between them and the port 17. For the operation of the valve three surfaces of the valve come into effect, one consisting of the forward end of the valve 26 which alone serves to drive the valve rearwardly. From this face of the valve the passage 27 leads to a port 28 in the cylinder, slightly forward of its central point. To this face also leads a passage 29 from the forward end of the inlet chamber 75 13. Opposed to this surface 26 are two smaller surfaces which serve to operate the valve in the other direction. One of these is the surface 30 which is always open through the ports 12 to the front end of the cylinder 80 and the other is the rear surface of the valve 15 which is made up of two surfaces, one the rear surface of a flange 31 on the valve and the other the surface 32 of the rear end of the valve. This surface is only all effective 85 110

when the valve is in its rearward position and the outer surface of flange 31 is in contact with the shoulder 33 on the side of the valve chest, as will be seen later. The total area of these surfaces is greater than that of the surface 26. From the inlet chamber 13 a small leak port 34 leads to the inlet port 17 so that it is at all times in communication with the cylinder while from the inlet chamber 13 a small leak port 35 leads into the extreme end of the cylinder, these two leak ports being for purposes which will later appear.

In operation, supposing the parts to be in the position shown in Fig. 1 the valve 15 having just been thrown rearwardly, air will enter the front end of the cylinder through the inlet chamber 13, restricted passages 16, ports 12 and passages 10 and 9 driving the piston to the rear. A very small amount of air is needed for this purpose as the recoil of the piston from the tool has a large effect in driving it back. As the piston moves rearwardly into the cylinder, air from the back end, is exhausted through the port 18 and port 20 and passages 21 to the atmosphere. It will be noticed that for a short portion of the stroke of the piston, until the rear end of it passes the port 28, the air can escape from the surface 26 through the passage 27 to the cylinder which is at atmospheric pressure, or nearly so, on account of the fact that the exhaust port 18 is open to atmosphere. Sufficient air however will be taken from the chamber 13 through the passage 29 to prevent the pressure of the surface 30 from throwing the valve forward again. When in its rearward travel the rear end of the piston covers the exhaust port 18 its rear end will have uncovered the port 28 and the same, or approximately the same, pressure will therefore be exerted against the surface 26 and the surface 30. As the piston moves past the port 18 it will trap a certain amount of air in the back of the cylinder, which will be compressed as the piston moves farther toward the end of the cylinder. This compression will be increased materially by the leakage of live fluid through the ports 34 and 35. This pressure will be directly exerted on the surfaces 31 and 32 and will, after the piston has traveled a short distance past the port 18, be sufficient to overcome the compression on the part of surface 26 which is not balanced by the pressure on the surface 30. This will move the valve forward opening communication between the inlet ports 14 and 17 and between the exhaust ports 11 and 20. By reason of the size of passage 9 and the exhaust ports 11 and 20 a very free exhaust is permitted from the front end of the tool. Fluid will thus be admitted into the rear end of the cylinder driving the piston again forward. As the piston moves forward,

at first the only pressure on the valve is on the surface 32, pressure on the rear surface of the flange 31 being counterbalanced by that on the forward surface, as the flange 31 is now out of contact with the shoulder 33. As the front end of the piston passes the port 28 the escape of fluid passing through passage 29 is prevented and pressure begins to build up against the surface 26. This is not sufficient to move the valve back, however, until the rear end of the piston uncovers the port 28 allowing the full live pressure in the cylinder to pass through the passage 27 against the surface 26. The valve is then thrown rearwardly and the cycle, above described, repeated.

It will be seen from the above description that the air driving the piston has free access to the cylinder to drive it forward and is not cut off until practically the forward end of the stroke. The large exhaust passages from the front end at the same time allow the air from in front of the piston to escape freely, the result being a heavy uncushioned blow by the piston on the rivet set. By reason of the restricted area of the inlet passages 16 for the forward end of the cylinder a very small amount of air is admitted to the cylinder on the rearward stroke of the piston, the return being accomplished largely by the recoil of the piston. The air used in the tool is largely expended therefore on the effective stroke of the piston the result being a tool of high efficiency and economy for the purpose.

It is to be understood that the present showing and description discloses only one specified modification of my invention and other forms and modifications are included in the spirit and scope of the invention as expressed in the claims.

What I claim is:

1. In a percussive tool, a cylinder, its piston, a valve chest, inlet and exhaust passages for the rear end of the cylinder, a fluid passage extending rearwardly of the cylinder from the forward end of the cylinder to said valve chest, a valve supporting stem extending rearwardly from said forward passage, said stem having exhaust and inlet ports therein communicating with said forward passage, an exhaust opening in said valve chest, an inlet passage and a valve sliding on said valve supporting stem and adapted to alternately connect said exhaust ports and passages and said inlet ports and passages.

2. In a percussive tool, a cylinder, its piston, a valve chest, inlet and exhaust passages for the rear end of the cylinder, a fluid passage of large area extending rearwardly of the cylinder from the forward end of the cylinder to said valve chest, a valve supporting stem extending rearwardly from said large passage, said stem having exhaust

and inlet ports therein communicating with said large passage, an exhaust opening of large area in said valve chest, an inlet passage of very constricted area, and a valve 5 sliding on said valve supporting stem and adapted to alternately connect said exhaust ports and passages and said inlet ports and passages.

3. In a percussive tool, a cylinder, its piston, a valve chest, inlet and exhaust ports opening from said valve chest to the rear end of the cylinder, a passage of large area extending rearwardly of the cylinder to said valve chest, a valve supporting plug in said 15 valve chest having inlet and exhaust ports opening from said large passage to said valve chest, and an inlet passage of constricted area for the front end and an inlet passage for the back end opening from the 20 inlet of the tool to said valve chest, an atmospheric exhaust from said valve chest, and a valve sliding on said valve plug, adapted to connect said valve plug exhaust with said atmospheric exhaust, and said 25 rear end valve plug inlet with said rear end cylinder inlet, and in its other position to connect said rear end cylinder exhaust with said atmospheric exhaust and said constricted valve plug inlet passage with said 30 valve plug inlet port.

4. In a percussive tool, a cylinder, its piston, inlet and exhaust passages for both ends of the cylinder, the inlet port for one end being constricted in area, and the exhaust port for the other end being at a distance from the end of the cylinder, a valve 35 for controlling said passages having a surface for operating it in one direction and two smaller surfaces of a greater total area 40 than said first surface for operating it in the opposite direction, one of said smaller surfaces being in communication with each end of the cylinder, a passage from the intermediate portion of the cylinder to the 45 first surface, so placed as to be uncovered on both strokes by the piston, so that at the end of one stroke the first surface and one of said smaller surfaces will be exposed to live fluid pressure, while at the end of the

other stroke, said first surface and the other 50 of said smaller surfaces will be exposed to live pressure lessened by said constricted passage and the first of said smaller surfaces will be exposed to piston compression.

5. In a percussive tool, a cylinder, its 55 piston, inlet and exhaust ports communicating with the forward end of the cylinder, an inlet port for the rear end of the cylinder, an exhaust port farther from the rear end of the cylinder than said inlet 60 port and a valve for controlling said ports, having a surface for operating it in one direction and two smaller surfaces of a total area greater than said first surface for operating the valve in the other direction, 65 one of said smaller surfaces communicating with each end of the cylinder, a passage leading from the cylinder to said first surface and so placed as to be uncovered by the piston near the end of each stroke, so that 70 at the end of the forward stroke the first surface and one of the smaller surfaces will be exposed to live pressure, while at the end of the rearward stroke, the first surface and one of the smaller surfaces will be exposed 75 to live pressure and the other smaller surface will be exposed to the pressure of the fluid trapped by the piston in the rear end of the cylinder.

6. In a percussive tool, a cylinder, its piston, inlet and exhaust passages for both ends of the cylinder, a valve for controlling said 80 passages having a surface for operating said valve in one direction and two smaller surfaces of greater total area than said first 85 surface for operating the valve in the other direction, and passages so arranged that fluid pressure will be exerted on said first surface and one of said smaller surfaces at one end of the piston stroke and on all said 90 surfaces at the other end of the piston stroke.

In testimony whereof, I have hereunto set my hand.
